C. S. BURTON

DOUBLE ACTING SOLENOID PUMP

Filed Feb. 9, 1923

UNITED STATES PATENT OFFICE.

CHARLES S. BURTON, OF OAK PARK, ILLINOIS, ASSIGNOR TO STEWART-WARNER SPEEDOMETER CORPORATION, OF CHICAGO, ILLINOIS, A CORPORATION OF VIRGINIA.

DOUBLE-ACTING SOLENOID PUMP.

Application filed February 9, 1923. Serial No. 618,171.

To all whom it may concern:

Be it known that I, CHARLES S. BURTON, a citizen of the United States, residing in the village of Oak Park, in the county of Cook and the State of Illinois, have invented certain new and useful Improvements in Double-Acting Solenoid Pumps, of which the following is a specification, reference being had to the accompanying drawings forming 10 a part thereof.

The purpose of this invention is to provide a solenoid operated pumping means for producing vacuum for vacuum fuel feed devices. It consists in the elements and features of construction shown and described as indicated in the claim.

In the drawings:—

Figure 1 is a side elevation showing a portion of the engine of an automobile 20 equipped with a device embodying this invention.

Figure 2 is an axial section of the solenoid and pumping device.

Figure 3 is a section at the line 3—3 on 25 Figure 2.

Figure 4 is a bottom plan view of the parts shown in Figure 2.

The device embodying the present invention may be mounted at any convenient position 30 on the automobile whose engine is to be served but it is designed with a view to being mounted as shown in Figure 1 alongside the vacuum tank when the latter is mounted in its customary position on the forward 35 side of the dash. The device as a whole, thus mounted, is indicated by the letter A in Figure 1. It comprises a pumping element which as shown consists of a sylphon, 1, mounted in a supporting frame or chamber, 40 2, and having an atmosphere vent, 3, controlled by the inwardly seating check valve, 4, and a suction connection, 5, leading to the vacuum chamber of the vacuum feed tank B, and controlled by an outwardly seating 45 check valve, 6. The closed end of the sylphon is attached to the stem, 7, of the solenoid core, 8. The solenoid in which this core reciprocates is double comprising two 50 independent magnet elements, 9 and 10, with their circuit windings, 11 and 12, arranged end to end so that the single core reciprocates in both solenoids. The solenoid core has a second stem, 13, at the opposite end 55 from the stem, 7, which terminates in an expanded head or abutment, 14, for encounter

at the opposite limits of the stroke of the core, with two levers, 16 and 17, fulcrumed on a bracket, 18, extending from the lower head, 19, of the solenoid mount, said levers being connected by a link, 20, to cause them 60 to have simultaneous movement when either is actuated by encounter of the abutment, 14, of the solenoid core stem. The lower head, 19, of the solenoid mount is formed with an integral bracket, 22, which carries the two 65 contacts, 23 and 24, between which the knife switch member, 35, is shifted, said knife switch member being carried by the lever, 17, being attached thereto by an insulating connector, 26. A lug, 27, extending down 70 from the bracket, 22, serves for attachment of one end of the spring, 28, which is stretched therefrom past the fulcrum of the lever, 16, and attached to the farther end of 75 said lever, which has a laterally projecting stud, 29, for making such connection, thus affording the snap action for the switch. From the source of electric energy, as the battery conventionally indicated at 30, and having one pole grounded as indicated at 30^a, 80 a circuit wire, 30^b, from the opposite pole leads to an insulated binding post, 31, on the bracket, 22, at which there is also connected the circuit wire, 33, which extends to the knife switch member, 35. The two opposite contacts for the knife switch, 23 and 24, are each mounted insulated upon the bracket, 22, and have circuit connections, 37 and 38 respectively, running to the windings, 11 and 12, of the two solenoids. Said 85 windings are both grounded as indicated at 40, being intermediately extended to a manually operated cut-out switch, 42, which for convenience may be mounted on the dash as seen in Figure 1. 90

The operation of this device will be obvious from the above description being that upon the operator's closing the cut-out switch, 42, the circuit will be closed through the winding of the solenoid from which the core is at that time withdrawn, causing the core to be shifted into the solenoid thus energized, whereupon the abutment, 14, on the solenoid stem encountering the end of the lever toward which it is moved in this movement of the core, reverses the position of the knife switch, the reversal occurring by means of the snap action at the completion of the solenoid core's stroke and again shifting the current to the winding of the other 105 110

solenoid, so that the core is immediately retracted to its first position, and thus the core is reciprocated by the automatic shifting of the current from one circuit to the other; and in this reciprocation of the core the sylphon is alternately contracted and expanded, producing the pumping action by virtue of the atmosphere and suction connections described in connection with the oppositely seating check valves.

I claim:—

A reciprocating motor comprising in combination a double solenoid having a core adapted to reciprocate between two positions to which the two solenoid members when energized respectively tend to draw it, circuits containing the two solenoid windings respectively; a snap switch device adapted at one position to close one of said circuits

and at another position to close the other circuit and operating connections from the reciprocating core for shifting said switch device from either of said positions to the other upon the arrival of the core at said core positions respectively, the snap switch comprising two levers having their fulcrums fixed with respect to the solenoid and terminating for encounter of an abutment carried by the solenoid core, and a link connecting said two levers for causing their movement to be simultaneous, one of said levers carrying the moving-contact member of the switch.

In testimony whereof I have hereunto set my hand at Chicago, Illinois, this 5th day of February, 1923.

CHARLES S. BURTON.
